UNITED STATES PATENT OFFICE.

WILLIAM EVENSEN, OF CHICAGO, ILLINOIS, ASSIGNOR TO GOSS PRINTING PRESS COMPANY, A CORPORATION OF ILLINOIS.

PLATE-CLAMPING MECHANISM FOR PRINTING PRESSES.

Application filed February 2, 1926. Serial No. 85,425.

My invention relates to printing presses and more particularly to plate clamping mechanisms for such printing presses.

My invention more specifically relates to 5 a plate clamping mechanism permitting a quick and easy change whereby a double page plate may be quickly clamped on the cylinder in lieu of two single page plates, and vice versa.

10 My invention further relates to an inner clip and means for quickly and expeditiously connecting it to, or removing it from, the clip rod to permit the change from clamping two single page plates, to clamping a double page plate, or vice versa.

15 Objects and advantages of the invention will be set forth in part hereinafter and in part will be obvious herefrom, or may be learned by practice with the invention, the 20 same being realized and attained by means of the instrumentalities and combinations pointed out in the appended claims.

The invention consists in the novel parts, constructions, arrangements, combinations 25 and improvements herein shown and described.

30 The accompanying drawings, referred to herein and constituting a part hereof, illustrate one embodiment of the invention, and together with the description, serve to explain the principles of the invention.

35 My present invention is an improvement upon my U. S. Patent 1,503,941, patented August 5, 1924, to the Goss Printing Press Company of Chicago, Illinois, as assignee.

Of the drawings:—

40 Fig. 1 is a longitudinal vertical section through a plate cylinder, equipped with my plate clamping mechanism, showing two one page plates locked to the plate cylinder;

Fig. 2 is a longitudinal vertical section, 45 similar to Fig. 1, but with the inner clip removed to permit a double page plate to be clamped to the plate cylinder;

Fig. 3 is a transverse vertical section on the line 3—3 of Fig. 1;

Fig. 4 is a perspective view of the inner clip provided with one form of latching mechanism;

50 Fig. 5 is a fragmentary horizontal section through the inner clip to more clearly illustrate the latching device.

In printing a newspaper, or other printed product, it is frequently desirable to change 55 from single page plates to double page

plates. To do this it is necessary to remove the inner movable clips so that the outer movable clips will clamp the double page plate against the fixed clip or abutment in the center of the plate cylinder. The removal of these inner clips takes considerable time and is very inconvenient because the end nut or nuts on the clip rods, which have to be removed, are in a groove beneath the surface of the plate cylinder.

By my invention I form a plate clamping mechanism in which the inner clip can be quickly and expeditiously connected to the clip rod, when it is desired to print from single page plates; or, when it is desired 70 to change and print from a double page plate, the inner clip can be quickly disconnected from the clip rod and removed from the plate cylinder, to be subsequently replaced when it is again desired to print from 75 single page plates instead of a double page plate.

I have shown in the drawings one embodiment of my invention in which the plate cylinder 1 is provided with the ordinary 80 fixed clip or abutment 2 in the center of the cylinder 1. The plate cylinder is also provided with the ordinary clip slot 3 having an enlarged opening 4. In the form of my 85 invention shown in Fig. 1, but to which my invention is not to be limited, the clip rod is formed in two sections, the inner clip rod 5 and the outer clip rod 6, the two sections being connected by cooperating screw-threads 7 on the clip rod 5 and female 90 screw-threads 8 on the outer clip rod 6. The operation of this divided screw-threaded clip rod is more fully described in my Patent 1,503,941 previously referred to.

The inner clip rod 5 is provided with an 95 elongated slot 9 within which works the end 10 of the screw plug 11 so that the inner clip rod 5 may move longitudinally, but is prevented from rotary movement, as described more in detail in my patent previously referred to.

In Fig. 1 of the drawings the inner single page plate 12 is clamped between the fixed clip or abutment 2 and the movable inner clip 13, the outer single page plate 14 being 105 clamped between the inner clip 13 and the outer clip 15. This inner clip 13 is provided with a nonscrew-threaded axial bore 114 to permit the free passage of the screw-threaded end 15 of the inner clip rod 5. On 110

this clip rod is mounted a nut 16 and also preferably a check nut 17, the nut 16 engaging the inner clip 13 to clamp the inner single page plate 12 against the fixed clip 2 or abutment 2. The inner clip rod 5 is provided with a notch 18 having shoulders 19 and 20. Mounted on one end of the inner movable clip 13 is a pivoted member in the form of a spring latch 21, one end 22 being pivoted to the clip 13 by the screw 23. The free end 24 is preferably provided with a handle 25, one end of which is upset at 26 to secure the handle to the latch 21, and also to form a locking member which will snap into a depression 27 in the inner clip 13. The resilience of the latch 21 is such that when the locking member 26 is brought into register with the depression 27, the latch will snap into its locked position and be held in that position.

When it is desired to remove the inner single page plate 12 and the outer single page plate 14 the inner clip rod 5 and the outer clip rod 6 are operated in the manner described in my patent, previously referred to, which will move the clip rods to the left of Fig. 1. The shoulder 19 on the inner clip rod 5 will engage with the latch 21 and cause the inner clip 13 to be moved to the left a sufficient distance to free the inner single page plate 12, so that it can be removed and another single page plate substituted for it if desired. When the clip rods 5 and 6 move to the left the outer clip 15 releases the other single page plate 14, so that another single page plate may be substituted for it, if desired.

When it is desired to change from two single page plates 12 and 14 to a single double page plate 30 (Fig. 2), this can readily be done by pulling up on the handle 25 on the latch 21, the inner plate 12 having previously been removed, so that the latch will assume the dotted position shown in Fig. 4, clearing the shoulder 19 in the clip rod 5. It is then a very simple matter to move the inner clip 13 along the clip slot 3 until the opening 4 is reached when the inner clip 13 can be readily removed from the plate cylinder 1. This leaves the plate clamping mechanism ready to clamp a double page plate 30 (Fig. 2) between the outer clip 15 and the fixed clip or abutment 2.

When it is desired to change back from a double page plate 30 to two single page plates 12 and 14 shown in Fig. 1, this can readily be done by removing the plate 30, and then repositioning the inner clip 13 in the opening 4, and sliding it along the clip slot 3 to the left until it assumes its original position in engagement with the nut 16, when the handle 25 is pressed down by the operator causing the locking surface 26 to snap into the recess 27 in the inner clip,

thereby bringing the latch 21 into its operative position to cooperate with the shoulder 19 on the inner clip rod 5.

While I have described simply one clamping mechanism it is of course to be understood that a plurality of such clamping devices are employed to hold each plate, as described in my patent previously referred to, and that each inner clip would have to be removed to permit the clamping of a double page plate.

It will be seen that my invention is very simple and convenient to operate, and that it will save a great deal of time which is one of the most important factors in printing a newspaper or other printed product.

The invention in its broader aspects is not limited to the specific mechanisms shown and described but departures may be made therefrom within the scope of the accompanying claims without departing from the principles of the invention and without sacrificing its chief advantages.

What I claim is:

1. In a plate clamping mechanism for printing presses, the combination of a clip rod provided with a recess, a clip, and means carried by the clip to cooperate with the recess in the clip rod to limit the movement between the clip and clip rod.
2. In a plate clamping mechanism for printing presses the combination of a clip, a clip rod, one of said members being provided with a recess and the other member with a latch to cooperate with the recess.
3. In a plate clamping mechanism for printing presses the combination of a clip rod, a clip, and pivoted means to connect and disconnect the clip to the clip rod.
4. In a plate clamping mechanism for printing presses the combination of a clip rod, a clip, and pivoted means secured to the clip to connect and disconnect the clip to the clip rod.
5. In a plate clamping mechanism for printing presses, the combination of a clip rod, a clip, and a pivoted latch to connect and disconnect the clip to the clip rod.
6. In a plate clamping mechanism for printing presses, the combination of a clip rod, a clip, and a pivoted spring latch to connect and disconnect the clip to the clip rod.
7. A new article of manufacture comprising a clip to hold printing plates on a plate cylinder, said clip being provided with pivoted means to engage and disengage a clip rod.
8. A new article of manufacture comprising a clip to hold printing plates on a plate cylinder, said clip being provided with a pivoted spring latch to engage and disengage a clip rod.
9. A new article of manufacture comprising an inner clip to hold printing plates

on plate cylinders, said inner clip being provided with a non-threaded bore and with means to engage and disengage a clip rod.

10. A new article of manufacture comprising a clip to hold printing plates on a plate cylinder said clip being provided with a pivoted spring latch to engage and disengage a clip rod, and a handle on the spring latch.

11. A new article of manufacture comprising a clip to hold printing plates on a plate cylinder said clip being provided with a pivoted spring latch to engage and disengage a clip rod, and locking means to hold

the free end of the spring latch in a predetermined operative position upon the clip.

12. A new article of manufacture comprising a clip to hold printing plates on a plate cylinder said clip being provided with a pivoted spring latch to engage and disengage 20 a clip rod, locking means to hold the free end of the spring latch in a predetermined position upon the clip, and a handle on the spring latch.

In testimony whereof, I have signed my 25 name to this specification.

WILLIAM EVENSEN.
